[57] CLAIM

The ornamental design for a bracelet, as shown and described.

DESCRIPTION

FIG. 1 is a perspective view of a bracelet showing my new design;

FIG. 2 is an exploded perspective view of the fastener link thereof, the remainder of the bracelet being omitted for ease of illustration;

FIG. 3 is an edge view of one link and the two connectors adjacent either end, all other links and connectors being the same; and

FIG. 4 is a front elevational view thereof.
